LE ROY WILLOUR,
FLUSH VALVE,
APPLICATION FILED JULY 15, 1915.

1,177,001.

Patented Mar. 28, 1916.

UNITED STATES PATENT OFFICE.

LE ROY WILLOUR, OF ASHLAND, OHIO.

FLUSH-VALVE.

1,177,001.

Specification of Letters Patent. Patented Mar. 28, 1916.

Application filed July 15, 1915. Serial No. 40,042.

To all whom it may concern:

Be it known that I, LE ROY WILLOUR, a citizen of the United States, residing at Ashland, in the county of Ashland and State of Ohio, have invented certain new and useful Improvements in Flush-Valves, of which the following is a specification.

My invention relates to improvements in flushing apparatus for use in connection with toilet bowls, while not necessarily restricted to such use.

An important object of the invention is to provide means of the above mentioned character, having no float means for controlling its operation.

A further object of the invention is to provide means of the above mentioned character, which are strong, durable, simple in construction, and inexpensive to manufacture.

Other objects and advantages of the invention will be apparent during the course of the following description.

In the accompanying drawings forming a part of this specification and in which like numerals are employed to designate like parts throughout the same, Figure 1 is a side elevation of apparatus embodying my invention, showing the same in use, Fig. 2 is a central vertical longitudinal sectional view through the valve casing, associated elements being shown in elevation, Fig. 3 is a transverse vertical sectional view taken on line 3—3 of Fig. 2, Fig. 4 is a horizontal sectional view taken on line 4—4 of Fig. 2, and, Fig. 5 is a plan view of a water impinging element or tray.

In the drawings, wherein for the purpose of illustration is shown a preferred embodiment of my invention, the numeral 10 designates a toilet bowl of any well known or preferred type.

The numeral 11 designates a preferably horizontally arranged casing or shell embodied in a valve structure. This casing is provided near one end with a depending outlet pipe or tube 12, which is connected with the bowl 10, and discharges therein. Connected with the upper portion of the casing 11, near its opposite end, is a tubular extension or pipe 13, connected with a pressure water holding tank 14, by a coupling 15, of any well known or preferred type. This tank 14 is preferably provided with an inwardly opening air supply check valve 14', of any well known or preferred type, the

function of which is to prevent the air from being exhausted from the tank 14 during its operation. While I prefer to employ this valve, yet I have found that the apparatus will operate with some degree of success without it. Connected with the tubular extension or pipe 13 is a water supply pipe 16, of smaller diameter and having connection with a source of water under suitable pressure.

The upper end 17 of the discharge pipe or tube 12 constitutes a valve seat for engagement with a main vertically movable valve 18, to cover and uncover the intake end of the pipe 12. This vertically movable main valve, as more clearly shown in Fig. 3, is provided with vertical apertured knuckles 19, between which is arranged an apertured knuckle 20, these knuckles being pivotally connected by a pin 21, as shown. Connected with the knuckle 20 and preferably formed integral therewith is an upstanding loop or apertured element 22, for a purpose to be described. The loop 22 has a guide member 23 rigidly connected and preferably formed integral therewith, such guide member operating in a vertical opening 24, formed in a removable cap 25, having screw-threaded engagement with the upper end of the casing 11. As more clearly shown in Fig. 3, the main vertically movable valve 18 is provided with a central opening 26, constituting a valve seat for a pressure relief valve 27, vertically movable with relation to the main valve. The pressure relief valve 28, when unseated, contacts with the knuckle 20 and through it, elevates the main valve 18.

Disposed within the pipe or tube 12 beneath the depending portions 28 of the valve 27 is a vertically swinging cam element 29, rigidly mounted upon a rock-shaft 30. This rock shaft is journaled through openings in the pipe 12 and is horizontally arranged. The rock-shaft 30 extends outwardly beyond the pipe 12 and has a crank 31 rigidly connected therewith. Pivotally connected with the outer end of the crank 31 is a link 32, pivotally connected with one end of a vertically swinging lever 33, which is pivotally supported at 34. The lever 33 is bent outwardly suitably so that it does not contact with the bowl 10 when swung upwardly.

Arranged within the body portion of the casing 10 is a normally substantially horizontal vertically swinging lever 35, apertured at 36 for receiving a stationary pivot

element 37, attached to the casing 11 by any suitable means. Adjacent its pivot the lever 36 is provided with a crank 38, extending within the loop 22, as shown. Connected with the opposite or free end of the lever 35 and preferably formed integral therewith is a water impinging element or tray 39, preferably arranged at a slight angle thereto. The tray 39 is arranged directly beneath the discharge end of the pipe 13, whereby the water flowing through this pipe will directly impinge upon the tray 39 and move it downwardly. The tray 39 is preferably provided with apertures 40. The main valve 18 and pressure relief valve 27 and associated elements are substantially heavier than the tray 39 and the long arm of the lever 35, whereby, in the absence of the water impinging against the tray 39, the tray will be held in the elevated position.

As more clearly shown in Fig. 3, the end of the casing 11 adjacent the tray 39 is preferably formed open and covered by a removable plug 41, having screw-threaded engagement therewith.

In the operation of the apparatus, with the main valve 18 and pressure relief valve 27 closed, the water passes through the pipe 16 and of course first fills the casing 11. This water then backs up through the pipe 13 into the pressure casing or shell, entrapping air, which is compressed in the top of the casing 14. When the operator swings the lever 33 upwardly, the cam 29 is turned upwardly with the shaft 30, and contacts with the lower end of the extension 28 of the pressure relief valve 27. The water begins to pass through the opening 26, which breaks the pressure and permits of the easy opening of the main valve 18, upon the further vertical movement of the pressure relief valve 27, such pressure relief valve contacting with the knuckle 20, to elevate the valve 18. When this valve 18 is elevated or unseated the water drops or rushes downwardly through the pipe 13 and impinges upon the tray or element 39, thus retaining it in the lowered position during the emptying of the casing 14. The tray 39 holds the lever 35 in the lowered position, which in turn retains the valve 18 open. When all or practically all of the water has discharged from the casing 14, the main valve 18 and pressure relief valve 27 automatically gravitate to the lower or closed position, swinging the tray 39 upwardly to the normal raised position. The water is again fed through the pipe 16 into the casing 11, and subsequently into the pressure storage tank 14.

It is to be understood that the form of my invention herewith shown and described is

to be taken as a preferred example of the same, and that various changes in the shape, size, and arrangement of parts may be resorted to without departing from the spirit of the invention or the scope of the subjoined claims.

Having thus described the invention, I claim:

1. The combination with a casing, of a main valve to control the discharge of water from the casing and provided with upstanding knuckles, a pressure relief valve carried by the main valve, an inner knuckle arranged between the first named knuckles and pivotally connected therewith and adapted to contact with the pressure relief valve upon its upward movement, a member arranged beneath the pressure relief valve to elevate it, water inlet means connected with the casing, and a vertically swinging lever arranged within the casing and having one end connected with the inner knuckle and its opposite end provided with a tray disposed beneath the water inlet means.

2. The combination with a casing provided near one end with an approximately vertical water inlet pipe and near its opposite end with a depending outlet pipe, an upwardly opening valve for controlling the passage of water through the outlet pipe, means to raise the valve, a vertically swinging lever pivotally mounted within the casing and having operative connection with the valve, and a tray rigidly connected with the free end of the vertically swinging lever and disposed beneath and adjacent the inlet pipe whereby the incoming water impinges upon the tray.

3. The combination with a casing provided near one end with an approximately vertical water inlet pipe and near its opposite end with a depending outlet pipe, an upwardly opening valve for controlling the passage of water through the outlet pipe, an upstanding shank connected with the valve and provided with an elongated opening, a vertically swinging lever pivotally mounted within the casing and provided near its pivot with a crank extending into the elongated opening of the shank, a tray rigidly connected with the free end of the lever and arranged beneath and adjacent the inlet pipe whereby the incoming water impinges upon it, and means to raise the valve to open it.

In testimony whereof I affix my signature in presence of two witnesses.

LE ROY WILLOUR.
